United States Patent Office

Des. 221,706
Patented Aug. 31, 1971

221,706

VOLUMETRIC INFANT FEEDING UNIT

Robert Emmet Harrigan, Westerville, Ohio, assignor to
Abbott Laboratories, North Chicago, Ill.

Filed Nov. 5, 1969, Ser. No. 19,945

Term of patent 14 years

Int. Cl. D9—01; D24—05

U.S. Cl. D83—8

FIG.2

FIG.1

FIG.3

FIG. 1 is a front elevation of a volumetric infant feeding unit showing my new design;

FIG. 2 is a top plan view thereof; and

FIG. 3 is a plan view thereof.

I claim:

The ornamental design for a volumetric infant feeding unit, substantially as shown and described.
